UNITED STATES PATENT OFFICE.

ROBERT L. WELCH, OF CHICAGO, ILLINOIS, ASSIGNOR TO A. G. SPALDING & BROS., A CORPORATION OF NEW JERSEY.

MASK.

1,172,330.

Specification of Letters Patent. Patented Feb. 22, 1916.

Application filed May 18, 1915. Serial No. 28,882.

To all whom it may concern:

Be it known that I, ROBERT L. WELCH, a citizen of the United States, residing at Chicago, Illinois, have invented certain new and useful Improvements in Masks, of which the following is a specification.

My invention relates to certain detailed improvements more particularly herein-after set forth in baseball masks.

10 It is my main object to thoroughly and effectually brace the framework of the mask, so as to thoroughly sustain all possible strain, particularly about the center opening.

15 The invention also relates to the details of construction hereinafter set forth.

In the accompanying drawings Figure 1 is a side elevation, and Fig. 2 a front view of the mask embodying my improvement, 20 while Fig. 3 is a detail.

In the main, the mask is of ordinary type, made up of a main frame *a* from which two semicircular cross wires extend, as at *b*, *b'*, and integral with or independent of these 25 wires there are protruding sections extending rearwardly of the frame *a*, as shown at *c*, and against these the cushion section *d* is braced, being suitably secured in position by lacing. From the cross sections *b*, *b'*, the 30 usual network of wires extend downwardly and upwardly, and the main frame *a* is strengthened by approximately parallel sections *e* secured at top and bottom to the main section *a*, but running parallel there- 35 with through their main extent, and in connection with crossing wires.

My main object is to securely brace the mask at the arch of the wires *b*, *b'*, which border the eye opening in the mask, as I 40 have found that the ordinary network of wires extending longitudinally and cross-wise are not sufficient to withstand all the strain to which these masks are subjected, and I therefore have arranged a very sim- 45 ple construction which most effectually cooperates with the rest of the construction to positively brace the crossing wires at the point where most of the strain comes and

where these wires are weakest, namely: directly in the center. To attain this object 50 I take a section of wire *f* and bend it approximately into V-shape, fastening the apex of the V to the wire *b* by a suitable confining device, the ends of the wire *f* being suitably secured to the main frame *a*. 55 The wire *f* not only thus presents practically two straight bracing rods, extending from the main frame to the center arch, but they are slightly inclined upward so as to add to the bracing effect. I strengthen the lower 60 arch in exactly the same way except that the wire *f'* forming the stays or braces inclines downwardly slightly.

In order to give the greatest security to the connection between the bracing wire 65 and the arch, I use a sheet metal clip *g* one end of which embraces the apex of the brace member *f*, and is curved under the arch member *b*, while two ears of this clip 70 *h* encircle the diverging wire sections *i*, the lower ends of which are also embraced by the clip. The clip is given, as shown in the drawing, a curved form, and adds very materially to the strength of the entire construction. The lower connection is made 75 by a like clip in like manner, except that by reason of the fact that the wires *i* of the lower section are doubled, the lower clip *g'* is a little wider.

I do not limit myself to the exact arrangement of the wires constituting the mask, as these may vary, my aim being to secure a direct bracing effect for the arching members and to assure the strongest kind of connection between the bracing and arching 85 members.

I claim as my invention:—

1. In a baseball or like mask having a main frame and arching members extending therefrom, of cantaliver bracing sections *f* 90 extending from the crown of the arch to opposite sides of the main frame in straight lines and inside the wires of the mask proper, substantially as described.

2. In a baseball mask, a main frame, wire 95 sections extending therefrom, including

arching members, a cantaliver bracing member extending in a straight line from the crown of each arched member to the side of the main frame and wholly inside the
5 wires of the mask proper, and a clip for holding the arched and braced members together, substantially as described.

In testimony whereof, I affix my signature in presence of two witnesses.

ROBERT L. WELCH.
